UNITED STATES PATENT OFFICE.

JAMES FRANCIS HILL AND CHARLES MANAHAN PECKHAM, OF NORWALK,
OHIO.

MOLD.

No. 854,214.

Specification of Letters Patent.

Patented May 21, 1907.

Application filed November 26, 1906. Serial No. 345,137.

To all whom it may concern:

Be it known that we, JAMES FRANCIS HILL and CHARLES MANAHAN PECKHAM, citizens of the United States, residing at Norwalk, in the county of Huron and State of Ohio, have invented certain new and useful Improvements in Molds; and we do declare the following to be full, clear, and exact description of the invention, such as will enable others skilled in the art to which it appertains to make and use the same.

This invention relates to improvements in molds for manufacturing burial vaults and like structures from concrete or other plastic material, and has for its object to provide a simple apparatus of this character which may be adjusted to vaults or other structures of various sizes.

With these and other objects in view, the invention consists of certain novel features of construction, as hereafter shown and described and specifically pointed out in the claims.

In the drawings forming a part of this specification and in which corresponding parts are denoted by like designating characters, is illustrated any preferred form of the embodiment of the invention capable of carrying the same into practical operation.

The improved device may be employed for molding articles or structures of various kinds such as burial vaults, bath tubs, laundry tubs, sinks, and the like, but is more particularly designed for manufacturing burial vaults and like structures, and for the purpose of illustration, an apparatus for constructing a burial vault is shown in the drawings, in which

Figure 1 is a longitudinal section of the mold for making the body portion of the vault; Fig. 2 is a section on the line 2—2 of Fig. 1; Fig. 3 is a section on the line 3—3 of Fig. 1. Fig. 4 represents perspective views of the corner members; Fig. 5 is a sectional detail, enlarged, illustrating the manner of applying the lifting handles to the body of the structure; Fig. 6 is a longitudinal section, and Fig. 7 is a transverse section of the cover molding portion of the device; Fig. 8 is a sectional detail illustrating the manner of attaching the lifting members of the cover structure of the device; Fig. 9 represents perspective views of the auxiliary plates associated with the inner shell of the device;

and Fig. 10 is a sectional detail illustrating the manner of varying the sizes of the cover molding portion of the structure.

The portion of the improved device employed in constructing the body of the vault consists of an inner shell conforming exteriorly to the inner face of the body, an outer shell spaced from the inner shell, and conforming interiorly to the outer face of the body, and between which shells the plastic material is inserted, the outer shell being adjustable, or adapted to be enlarged slightly, to provide a space for the insertion of a coating material after the body portion has been embedded and allowed to "set" for a certain pre-determined period. The shells are also made adjustable to adapt them to bodies of different sizes, and the cover shell is provided with a plurality of "filler" members, to correspond to the adjustments of the shells, when bodies of different sizes are to be manufactured. The outer shell is provided with a plurality of strengthening bars arranged transversely of each other, and the inner shell is likewise provided with a plurality of similar strengthening bars.

The shells are constructed from sheet metal or other suitable material, or plate metal of suitable strength, and the strengthening bars are preferably of "T" metal or "L" metal, as may be preferred. The outer shell is represented as a whole at 10, its interior conforming to the exterior face of the body to be molded, and the inner shell is represented as a whole at 11 with its outer face conforming to the inner face or surface of the body to be molded. The outer shell is provided with strengthening bars 12, any required number being employed, the bars being preferably constructed from "T" metal, and bearing upon the interior face of the inner shell are like bars 13. The bars 12 and 13 are riveted or otherwise secured to their respective shells. The outer shell is oblong in shape, as shown, the side members being designated specifically by the characters 14—15 and the end members by the characters 16—17.

At their free ends, the side members 14—15 are provided respectively with rabbeted cleats 18—19—20—21, with interior shoulders, and fitting between these shoulder portions are corner plates 22—23—24—25, the corner plates curved interiorly to correspond to the curved junctures of the parts 14, 15,

16 and 17. The ends 16—17 of the outer shell are provided with rabbeted cleats 26—27, 28—29 with interior shoulders for engaging the inner edges of the corner members, 5 and thus completing the outer shell structure. The body members of the shell being of sheet metal and the the corner members being of cast metal, are necessarily thicker than the sheet metal body of the shell, but the 10 shoulders within the rabbeted members cause the inner faces of the corner members to correspond with the inner faces of the sheet metal shell members, as shown. With a structure thus arranged, the shells may be 15 widened or lengthened to any required extent by simply substituting corner members of different sizes, as will be obvious.

The side portions 14—15 and end portions 16—17 will correspond in length to the smallest vault required, and by providing a plurality of the corner members, corresponding to the different sizes of vault required, any size may thus be constructed, as will be obvious.

The corner members and the rabbeted 25 cleats are bolted as at 30 to the body of the shell and to each other, so that they can easily be detached when required.

The holes for the bolts 30 are slotted longitudinally of the vault structure, so that the 30 size of the outer shell may be increased slightly to provide for introducing a coating material for the completion of the body of the vault.

The inner shell is formed substantially in 35 the same manner as the outer shell, with spaced sides 32—33 and spaced ends 34—35. The ends and sides of the inner shell are provided with rabbeted cleats 36—37—38—39—40—41—42—43 similar to the cleats of the outer shell except that they are disposed in reverse position, and bearing at one edge against the shouldered cleats are corner members 44—45—46—47, the latter being similar to the corner members of the outer shell.

45 The corner members will be furnished in sets corresponding to the sizes of the vaults to be constructed, to enable the operator to "adapt" the mold for any required size of vault, as will be obvious.

50 The side members 32—33 of the inner shell are connected by a sheet metal plate 60, which forms the surface for supporting the material which forms the bottom of the vault when the latter is molded, the member 55 60 being strengthened by suitable stays 61, of "T" bars or the like. The vault is molded upside down and the bottom thereof is troweled off even with the edges of the outer mold.

60 The body members 32—33—34—35 and 60 of the inner shell with its cleats will be constructed for the smallest vault required, and the gap otherwise left between the end of the plate 60 and the closures 34—35 will be 65 filled by removable filler sheets or plates rep-

resented at 62 when larger vaults are required and a plurality of these sheets will be furnished conforming to the sizes of the corner members.

The shells will be disposed upon a suitable 70 base represented at 63, and the portion of the outer shell bearing upon the base will be enlarged laterally, to provide a laterally extending rim to the structure to be molded, plates 32—33—34 and 35 riveted thereon 75 near their edges, strips of metal as 64 and the corner irons have cast thereon strips or ribs similar to the ribs 64, which form a channel in the rim of the molded structure, to receive the lower edge of the cover member of 80 the structure, as hereafter explained. After the two shells are disposed in position and the movable end closures adjusted as required, the two shells are connected at suitable intervals by tie bolts 65, to prevent the 85 separation of the shells by the pressure of the material which forms the molded structure, these bolts to be removed after the molding operation is completed, and the holes left thereby filled with the plastic material, after 90 the shells are removed. After the shells are disposed in position, the material is poured into the space between the shells and flush with the upper edges of the outer shell, and the exposed surface which forms the bottom 95 of the molded structure smoothed off by "troweling," or by other suitable means. After the material has partially "set," or become sufficiently hard to prevent it from flowing, the tie bolts 65 are removed, and the 100 shells allowed to remain until the material is set sufficiently to permit the removal of the shells.

The holes formed by the tie-bolts, and other cavities are filled with the plastic material of which the structure is composed, and troweled smooth, and other irregularities of the structure corrected in the same manner.

Suitable handles represented at 66 may be attached to the molded structure at suitable 110 points, as required, the inner fastenings of the handles being covered by the plastic material as represented at 67, after the shells are removed.

The mold 50 for the cover of the body portion of the molded structure is represented in Figs. 6, 7 and 8, and comprises an outer shell 51 curved transversely and with semi-circular ends, and preferably constructed from a single sheet of sheet steel pressed into the required shape, and conforming interiorly with the outer surface of the molded cover structure, the shell 51 being provided with suitable supporting members, preferably of "T" metal, as shown at 52.

The material for the body portion of the cover is placed in the mold and its inner surface formed by a suitable "sweep" implement represented at 53, and the ends formed by disposing suitably shaped blocks 54 at the 130

ends, between which and the curved ends of the shell the material to form the ends of the cover structure is deposited, the inner surface being finished by troweling before the shell is removed.

Bolts 55 are inserted through the outer shell and project through the material forming the cover structure, to form recesses or cavities to receive eye-bolts 56, which are inserted after the material has "set" sufficiently to permit the shell 51 to be detached, the eye-bolts having inner heads 57 which are covered by a plastic material and the surface finished by troweling in the ordinary manner, the eye-bolts forming means whereby the cover structure may be readily handled, as required.

The shell 51 will be constructed to correspond in length with the largest cover required, or with a cover to correspond to the longest vault, and a plurality of end blocks 54 will be provided of varying sizes, to correspond to the varying lengths of covers, and by inserting these varying sizes of blocks, it will be obvious that covers of varying lengths may be constructed within the same shell 51, the blocks 54 corresponding to the varying sized corner members of the body mold, as before described.

30 A projecting rib 58 will be formed upon the edge of the cover structure to enter the recess in the body structure formed by the rib 64, to provide a suitable joint between the cover and the body.

35 The supporting members of the outer body shell, the supporting members of the inner body shell, and the supporting members of the cover shell may be arranged in any required manner, and any required number 40 may be employed.

45 The inner shell of the body member is further strengthened by L-metal braces 67. It will be obvious that a very complete, simple, and easily operated structure is thus produced, and whereby vaults or other receptacles may be easily molded, and of any size and of any configuration.

The inner face of the outer body shell, and the inner face of the cover shell, may be 50 formed with any desired ornamental moldings, bands, or other similar ornamental fanciful designs. The body structure and the cover structure may also be provided with woven wire netting embedded within its 55 walls, as represented at 68, if required.

60 The corner members are constructed "rights" and "lefts," and are adapted to be reversed in position. The corner members are also so constructed that the length of the 65 mold will be increased by disposing the corner members in one position and the width increased by reversing the corner members.

If the mold is to be increased both in length and width, it will be necessary to furnish 65 other sets of the corner members of the re-

quired size. Molds of any required size may thus be readily constructed, as will be obvious.

Having thus described my invention, what I claim as new is:—

1. A device of the class described comprising an inner shell having end and side members, a plurality of corner members adapted to be detachably-connected with said inner shell at the ends of said side and end members, an outer shell having end and side members and spaced from said inner shell, and means for increasing the length and width of said outer shell. 75

2. A device of the class described comprising an inner shell having end and side members, a plurality of corner members adapted to be detachably connected to said inner shell at the ends of said side and end members, an outer shell having end and side members and spaced from said inner shell, and a plurality of corner members adapted to be detachably connected to the ends of the end and side members thereof. 85

3. A device of the class described comprising an outer and an inner shell spaced apart, means for widening and lengthening said outer and inner shells, whereby body portions of different sizes may be molded, a cover mold comprising a shell conforming interiorly 95 to the outer surface of the cover and of sufficient area to conform to the cover for the largest body portion, and a plurality of blocks of varying sizes adapted to be disposed within the cover shell and spaced therefrom, whereby cover structures of varying sizes may be 100 constructed.

4. A device of the class described comprising an inner shell formed of end and side members, cleats provided with varying shoulders 105 and connected to the ends of said inner shell end and side members, a plurality of sets of pairs of corner members of varying sizes adapted to engage with the shouldered cleats of the inner shell one pair at a time, an outer 110 shell formed of side and end members, cleats for varying shoulders and connected to said outer shell members at their ends, a plurality of sets of pairs of corner members of varying sizes adapted to engage the shouldered cleats 115 of the outer shell one pair at a time.

5. A device of the class described comprising an inner shell formed of end and side members, cleats provided with varying shoulders and connected to the ends of said inner shell 120 end and side members, a plurality of sets of pairs of corner members of varying sizes adapted to be engaged with the shouldered cleats of the inner shell one pair at a time, an outer shell formed of side and end members, 125 cleats having varying shoulders and connected to said outer shell members at their ends, a plurality of sets of pairs of corner members of varying sizes adapted to engage the shouldered cleats of the outer shell one pair at a 130

time, means for adjusting said cleats longitudinally of the said side and end members of said outer shell, whereby said outer shell may be spaced from the structure after the molding operation to permit the insertion of the coating element between the molded structure and the outer shell.

6. A device of the class described comprising an inner shell formed of end and side members, cleats provided with varying shoulders and connected to the ends of said inner shell end and side members, and provided with transverse slots, claimed and extending through said slots and the adjacent portions of the end and side members, a plurality of sets of pairs of corner members of varying sizes adapted to be engaged with the shoul-

dered cleats of the inner shell one pair at a time, an outer shell formed of side and end members, cleats having varying shoulders and connected to said outer shell members at their ends, and a plurality of sets of pairs of corner members of varying sizes adapted to engage the shouldered cleats of the outer shell one pair at a time. 25

In testimony whereof we have hereunto set our hand in presence of two subscribing witnesses.
